An ornamental design for a lamp, as shown and described.

DESCRIPTION

FIG. 1 is a perspective view of a lamp, in accordance with the present invention;

FIG. 2 is a side view of the lamp of FIG. 1;

FIG. 3 is a front view of the lamp of FIGS. 1 and 2;

FIG. 4 is a rear view of the lamp of FIGS. 1-3;

FIG. 5 is a top plan view of the lamp of FIGS. 1-4;

FIG. 6 is a bottom plan view of the lamp of FIGS. 1-5; and,

FIG. 7 is a cross-sectional view of the lamp of FIGS. 1-6, taken along line 7-7 of FIG. 5.

Portions of the power cord are shown broken away to indicate that no specific length is claimed.

In the drawings, the broken lines showing the remainder of the lamp illustrate features which form no part of the claimed design.
